UNITED STATES PATENT OFFICE

91,971

DESIGN FOR A FOOD CONTAINER

Lewis H. Scurlock, Chicago, Ill.

Application October 27, 1933, Serial No. 49,572

Term of patent 14 years

To all whom it may concern:

Be it known that I, LEWIS H. SCURLOCK, a citizen of the United States and resident of Chicago, in the county of Cook and State of Illinois, have invented a new, original, and ornamental Design for a Food Container, of which the following is a specification, reference being had to the accompanying drawing, forming a part thereof:

Fig. 1 is a plan view of a food container showing my new design.

Fig. 2 is a side elevation of said food container. The device of my design comprises the several elements shown in solid black lines in the drawing, combined with a base shown in dotted lines. The dominant features of the design are shown in the solid black lines.

I claim:

The ornamental design for a food container, as shown and described.
